UNITED STATES PATENT OFFICE.

PAUL D. MEIERS, OF GRANITE CITY, ILLINOIS.

COVER FOR TOOTH-BRUSHES.

1,213,235.

Specification of Letters Patent. Patented Jan. 23, 1917.

Application filed June 12, 1913. Serial No. 773,330.

To all whom it may concern:

Be it known that I, PAUL D. MEIERS, a citizen of the United States, residing at Granite City, in the county of Madison, State of Illinois, have invented certain new and useful Improvements in Covers for Tooth-Brushes; and I do hereby declare the following to be a full, clear, and exact description of the invention, such as will enable others skilled in the art to which it appertains to make and use the same.

The present invention is directed to improvements in covers for tooth brushes, and has for its object to provide a device of this character in the nature of a casing which can be easily and quickly engaged or disengaged from a tooth brush.

A further object of the invention is to provide a cover which when in place upon a tooth brush will entirely inclose the bristles so that should the same be damp the brush can be placed in a valise without the likelihood of the dampness therefrom soiling the articles contained in the valise.

A still further object of the invention is to provide a cover so constructed that the same can be suspended with the tooth brush contained therein, so that the brush will be protected from dust and germs.

With these and other objects in view, this invention resides in the novel features of construction, formation, combination and arrangement of parts to be hereinafter more fully described, claimed and illustrated in the accompanying drawing, in which:—

Figure 1 is a perspective view of the device. Fig. 2 is a longitudinal sectional view therethrough. Fig. 3 is a sectional view on line 3—3 of Fig. 1. Fig. 4 is a similar view on line 4—4 of Fig. 1.

The cover consists of sections 1 and 2, which are adapted to be arranged in telescoping relation so as to inclose the brush head 3, and bristles 4 thereof. The back 5 of the section 1 is elongated and is provided with a flange 6, one end of which is provided with a slot 7, which extends the entire depth of the flange and is adapted to receive the handle 8 of the brush. The section 2 is also

provided with an elongated back 9 and a 50 flange 10, one end of which is provided with a recess 11 which is adapted to register with the slot 7 of the flange 6 so as to engage the handle 8 adjacent the bristles 4, and when the sections are in telescopic relation. One 55 end of the back 5 of the sections 1 is provided with an eye 12, by which the cover can be suspended on a nail or the like with the bristles and head of the tooth brush inclosed thereby. 60

From the foregoing description it will be seen that a cover has been provided for tooth brushes which can be easily and quickly applied or removed therefrom, and one which when in place will effectually protect the 65 brush.

What is claimed is:—

1. In an adjustable tooth brush holder, an elongated plate having an outwardly extending flange formed adjacent its edge, said 70 flange having a slot formed therein extending from the edge thereof to the plane of the plate, and a second plate having an outwardly extending flange formed thereon, said last mentioned flange adapted to slidably engage with the first mentioned flange and having a depression in one edge thereof constructed and arranged to register with the aforementioned slot for receiving the handle of the brush, said flanges being adjustable to accommodate brushes with bristles of various length. 75

2. In a tooth brush holder, a flat elongated plate, a flange extending from the plate and provided with means to receive the handle 85 and permit the back of a tooth brush to rest flat against the plate within the flange, a second flat elongated plate, and a flange on the second plate slidably engageable with the first flange and provided with means to hold 90 the handle of the brush from movement away from the first plate.

In testimony whereof, I affix my signature, in the presence of two witnesses.

PAUL D. MEIERS.
